CLAIM

The ornamental design for a latch or lock housing with foldable handle, as shown and described.

DESCRIPTION

FIG. 1 is a top, front, and side perspective view of a latch or locking housing with foldable handle showing our new design;

FIG. 2 is a top, front, and side perspective view thereto, with the handle shown rotated to an alternative position;

FIG. 3 is a top, front, and side perspective view thereof, with the handle shown both rotated to an alternative position and extended; and

FIG. 4 is a top, rear, and side perspective view thereof.

FIG. 1

FIG. 2

FIG. 3

FIG. 4
